UNITED STATES PATENT OFFICE.

CHARLES PARADIS, OF LOWELL, MASSACHUSETTS.

SAFETY DEVICE FOR ELEVATORS.

No. 909,322.

Specification of Letters Patent.

Patented Jan. 12, 1908.

Application filed August 5, 1907. Serial No. 387,211.

To all whom it may concern:

Be it known that I, CHARLES PARADIS, a citizen of the United States, residing at Lowell, in the county of Middlesex and Commonwealth of Massachusetts, have invented a certain new and useful Improvement in Safety Devices for Elevators, of which the following is a specification.

This invention relates to safety devices 10 for elevators and comprises means herein-after described, whereby the person in charge of the elevator-car may stop the same instantly upon the too rapid descent of said car, due to any failure of the hoisting and 15 lowering machinery.

Sometimes elevator-cars provided with automatic safety devices, are raised by chains, the weight and drag of which when broken will prevent the springs from operating to effect the engagement of the dogs or catches with the safety-racks and sometimes the unbroken hoisting rope or chain unwinds so fast from the drum that the car attains a dangerous speed without said rope 25 or chain becoming slack enough to permit the expansion of said springs.

The safety device hereinafter described is directly in the control of the person in charge of the elevator, by means of a lever arranged 30 in proximity to the starting rope on which lever said person or elevator-man is expected to have his hand at all times while the elevator is being used, so that he may immediately operate the safety-device when the 35 car drops or attains a dangerous speed in the downward direction.

In the accompanying drawing, Figure 1, is a front elevation of the safety-device, omitting the controlling lever, applied to the 40 frame of a car, parts of said frame being shown in section; Fig. 2, a front elevation of said car and its guides, both of said guides being broken away to show the safety-racks; Fig. 3, a plan of the dog and hand-lever and 45 a horizontal section of the rack.

The elevator-car shown is of the common form used in factories and warehouses for elevating freight and comprises a platform A, uprights a a^1 and a cross-head a^2 connecting the upper ends of said uprights. Said car is raised and lowered by means of a rope, chain or similar flexible connection secured in any usual manner to a bolt b arranged in the cross-head a^2 , and is limited to a vertical 50 path by the guides C C^1 , also in the usual manner. Said guides support safety-racks

D D^1 provided with teeth d which point upwardly and are preferably inclined downward slightly on their tops at d^1 .

In a suitable stand b^1 , which is represented 60 as the head of the bolt b arranged below the cross-head, is pivoted a dog-lever E, at e , midway between its ends. Dogs or catches F F^1 are arranged to slide horizontally in sleeve-bearings f f^1 secured in the uprights 65 a a^1 and are connected by links f^2 f^3 to opposite ends of the lever E. The undersides of the outer ends of the dogs F F^1 are inclined downward and outward at f^4 f^5 to fit the tops of the teeth of the racks D D^1 and 70 the end-surfaces of said dogs should also be parallel with the rising parts of the teeth. A hand-lever G is pivoted at g on the upright a^1 and is provided at its lower end with a suitable handle g^1 adapted to be grasped by 75 one hand by the elevator-man, and said lever is provided at its upper end with a fork g^2 which receives a stud h which projects horizontally from a slide H arranged to move parallel with the dog F ^{1} in a way h^1 supported 80 on the upright a^1 . A connecting rod I is pivoted at one end at i to the link f^3 and at the other end at i^1 to said slide H.

When the handle g^1 is drawn towards the center of the elevator car, the dog F ^{1} is thrown 85 into engagement with the corresponding rack D ^{1} and through the links f^2 f^3 and the lever E simultaneously forces the dog F into engagement with the other rack D and prevents the further descent of the elevator-car. 90 The movement of the lever E in either direction is limited by the inclined surface b^2 of the stand b^1 to prevent said lever E from turning beyond the center and withdrawing the dogs from the racks. When the dogs are 95 engaged with the teeth of the rack, the weight of the elevator car presses said dogs down into said teeth with such force that it is impossible to reverse the hand-lever until said car is lifted by some means and this would be 100 the case ordinarily even if the dogs and teeth were not inclined or hooking as described, but the construction described is adopted for still greater safety.

A spring, represented as a helical spring J, 105 stretched between the cross-head a^2 and the link f^2 , normally holds the dog-lever E in the position shown in Fig. 1 and prevents the dogs F F^1 from being jarred into engagement with the racks. The racks are sufficiently 110 wider than the dogs to obviate any danger of the dogs being prevented from engaging the

racks by striking the guides at the sides of the racks, as shown in Fig. 3.

I claim as my invention:—

1. The combination of an elevator-car provided with a frame having uprights, stationary racks, dogs arranged to slide in said frame to engage said racks, a dog-lever, links, each connecting an end of said dog-lever to one of said dogs, a hand-lever supported on one of said uprights and connecting means between said hand-lever and one of said links, to move said dogs by the movement of said lever.

2. The combination of an elevator-car provided with a frame, stationary racks, dogs arranged to slide in said frame to engage said racks, a dog-lever, links each connecting an end of said dog-lever to one of said dogs, a hand-lever supported on said frame, a slide movable on said frame and engaged by said hand-lever, and a rod connecting said slide and one of said links.

3. The combination of an elevator-car provided with a frame, stationary racks, dogs arranged to slide in said frame to engage said

racks, a dog-lever, links, each connecting an end of said dog-lever to one of said dogs, a hand-lever supported on said frame and provided with a fork, a slide movable on said frame, and provided with a stud engaged by said fork, and a rod to connect said slide and one of said links.

4. The combination of an elevator-car provided with a frame having uprights, stationary racks, dogs arranged to slide in said frame to engage said racks, a dog-lever, links, each connecting an end of said dog-lever to one of said dogs, a hand-lever supported on one of said uprights, connecting means between said hand-lever and one of said links to move said dogs by the movement of said lever, and means for limiting the movement of said dog-lever.

In witness whereof, I have affixed my signature in presence of two witnesses.

CHARLES PARADIS.
